Primary Examiner—Stacia Cadmus*Attorney, Agent, or Firm*—Pretty, Schroeder & Poplawski, P.C.[57] **CLAIM**

The ornamental design for a wheel, as shown and described.

DESCRIPTION

FIG. 1 is a perspective view of a wheel showing my new design;

FIG. 2 is a reduced front elevational view thereof; and, FIG. 3 is a cross-sectional view thereof taken along the line 3—3 in FIG. 2.

The broken line disclosure in FIGS. 1-3 is for illustrative purposes only and forms no part of the claimed design. The rear of the wheel forms no part of the claimed design.

1 Claim, 3 Drawing Sheets*FIG. 1*

FIG. 2

FIG. 3
